US0D1038690S

(12) United States Design Patent (10) Patent No.: US D1,038,690 S
(45) Date of Patent: * Aug. 13, 2024

(54) COFFEE GRINDER

(71) Applicant: MAZZER LUIGI S.P.A., Scorzè (IT)

(72) Inventor: Marco Schnabl, Scorzè (IT)

(73) Assignee: MAZZER LUIGI S.P.A., Venice (IT)

() Term: 15 Years

(21) Appl. No.: 29/885,252

(22) Filed: Feb. 22, 2023

Related U.S. Application Data

(62) Division of application No. 35/513,146, filed on Nov. 30, 2021 (U.S. filing date under 35 U.S.C. 384), and having an international filing date of Nov. 30, 2021.
